United States Patent Office

Des. 175,226

Patented July 26, 1955

175,226

PHOTOGRAPHIC COPYING MACHINE

Harold L. Malone and Rex B. Husted, Rochester, N. Y.,
assignors to Eastman Kodak Company, Rochester,
N. Y., a corporation of New Jersey

Application December 24, 1954, Serial No. 33,673

Term of patent 14 years

(Cl. D61—1)

Fig. 1

Fig. 2

Fig. 1 is a perspective view of a photographic copying machine taken from the front and showing our new design; and

Fig. 2 is a view similar to Fig. 1 but taken from the opposite side of the photographic copying machine shown in Fig. 1.

We claim:

The ornamental design for a photographic copying machine, as shown.
